UNITED STATES PATENT OFFICE.

JOSEPH WINTGENS, OF POMEROY, WASHINGTON.

DRAFT-EQUALIZER.

No. 830,949.

Specification of Letters Patent.

Patented Sept. 11, 1906.

Application filed January 4, 1906. Serial No. 294,608.1

To all whom it may concern:

Be it known that I, JOSEPH WINTGENS, a citizen of the United States, residing at Pomeroy, in the county of Garfield and State of Washington, have invented certain new and useful Improvements in Draft-Equalizers; and I do declare the following to be a full, clear, and exact description of the invention, such as will enable others skilled in the art to which it appertains to make and use the same.

This invention relates to improvements in draft-equalizers.

The object of the invention is to provide a device of this character by means of which any number of teams may be hitched together and the draft on said teams equally distributed.

With the above and other objects in view the invention consists of certain novel features of construction, combination, and arrangement of parts, as will be hereinafter described and claimed.

In the accompanying drawings, Figure 1 is a plan view of a draft-equalizer constructed in accordance with the invention and arranged for twenty-four horses. Fig. 2 is an enlarged plan view of the rear and one of the supplemental draft-bars and equalizer. Fig. 3 is a vertical sectional view on the line 3-3 of Fig. 2 looking in the direction of the arrow, and Fig. 4 is a similar view on the line 4-4 of Fig. 2.

Referring more particularly to the drawings, 1 denotes the main draft-bar, arranged at the inner end of the tongue 2 of the vehicle or machine to which the equalizer is applied.

3 denotes a series of supplemental draft-bars, of which there may be any desired number, arranged one above the other, as shown in Fig. 1.

The draft-bars 1 and 3 are each preferably formed of upper and lower parallel bars suitably connected together. Pivots mounted between the upper and lower bars of the main draft-bar 1, on each side of the center thereof, is a pair of equalizing-levers 4. The equalizing-levers 4 of the main draft-bar 1 are pivotally connected near their inner ends to the tongue 2 by means of connecting rods or links. To the extreme inner ends of said equalizing-levers 4 are connected links 6, the outer ends of which are connected to a draft chain, cable, or other flexible draft element 7. The opposite end of the latter is connected to the inner ends of links 8, which are in turn

connected to the equalizing-levers 9, pivotally connected to the supplemental draft-bars 3. To the inner ends of the levers 9 of each of the supplemental draft-bars 3 are links 10, the outer ends of which are connected by chains or cables 12 with the equalizing-levers 9 of the next supplemental draft-bars ahead, except at the end of the equalizer, where said chain or cable is connected to a whiffletree 13, to the ends of which are connected swingletrees 14. The links 8 at the outer ends of each successive chain or cable are connected to the next forward equalizing-levers at the points nearer to the pivotal connection of said equalizing-levers on each successive draft-bar, thereby increasing the leverage of each successive pairs of equalizing-levers from the inner to the outer end of the draft device. Pivots mounted between the outer ends of the upper and lower bars of the main draft-bar are draft-trees 15, the pivotal connection of said draft-trees in the draft-bars being such that the inner end of the trees are of considerably greater length than the outer portion of the same. To the longer inner end of the draft-tree 15 are connected swingletrees 16, and to the outer shorter ends of said draft-trees are connected whiffletrees 17, to the ends of which are connected swingletrees 18.

In the outer ends of each of the supplemental draft-bars 3 are pivotally connected draft-trees 19, said draft-trees being pivotally connected to the supplemental draft-bars at the point nearer the outer ends of the same, so that the inner end or portion of the draft-trees is considerably longer than the outer portion thereof. To said inner and outer ends of the draft-trees 19 are connected whiffletrees 20, to the ends of which are connected swingletrees 21.

By providing an equalizer constructed and arranged as herein shown and described the draft will be evenly distributed to all the teams hitched thereto, and while the device is shown in the drawings as arranged for hitching twenty-four horses it is obvious that the capacity of the same may be increased or diminished without affecting the principal or operating qualities of the device.

From the foregoing description, taken in connection with the accompanying drawings, the construction and operation of the invention will be readily understood without requiring a more extended explanation.

Various changes in the form, proportion,

and the minor details of construction may be resorted to without departing from the principle or sacrificing any of the advantages of this invention as defined by the appended 5 claim.

Having thus described my invention, what I claim as new, and desire to secure by Letters Patent, is—

In a draft-equalizer, the combination with 10 a main draft-bar, of a series of supplemental draft-bars, a pair of equalizing-levers adjustably and pivotally connected at one of their ends on each of said draft-bars, flexible draft elements connecting said equalizing-levers at 15 successively greater distances from their piv-

otal connections with said draft-bars from the inner to the outer ends of said draft elements, whiffletrees connected to one end of each of said draft-bars, swingletrees connected to each end of each of said whiffletrees, 20 and swingletrees connected to the opposite ends of said whiffletrees, substantially as described.

In testimony whereof I have hereunto set my hand in presence of two subscribing witnesses. 25

JOSEPH WINTGENS.
